UNITED STATES PATENT OFFICE.

JEAN SÉNÉGAS, OF NEW YORK, N. Y.

SANITARY HOLDER FOR TOILET ARTICLES, &c.

1,171,262.

Specification of Letters Patent.

Patented Feb. 8, 1916.

Application filed March 29, 1915. Serial No. 17,793.

To all whom it may concern:

Be it known that I, JEAN SÉNÉGAS, a citizen of the United States, and a resident of the borough of Manhattan, city, county, and State of New York, have invented certain new and useful Improvements in Sanitary Holders for Toilet Articles, &c., of which the following is a specification.

My invention is designed to afford convenient and sanitary means for supporting, when not in actual use, toilet articles such as tooth brushes and shaving brushes and accessories like the tubes of dentifrice or soap ordinarily used in connection therewith,—the support being effected in such manner that all the articles are readily accessible at all times.

The invention consists in the construction and arrangement of parts described and claimed specifically, a distinctive feature being the arrangement of the brush support underneath a rest for a glass, shaving mug, or like receptacle, which latter may be thereby used as a canopy or shield for the brush, as hereinafter more fully set forth.

Incidentally the invention includes certain other details of construction whereby the holder and the glass or similar receptacle used in connection therewith are adapted to the support of sticks or tubes of material to be used in conjunction with the brush or brushes.

In the accompanying drawings, Figure 1, is a front elevation of my holder made in the form of a bracket; Fig. 2, a horizontal section taken upon plane of line 2—2, Fig. 1; Fig. 3, a central vertical longitudinal section taken upon line 3—3, Fig. 1; Fig. 4, a top view of the form shown in Fig. 1; Fig. 5, a front elevation of a modification of the holder.

The device consists essentially of a standard S, formed at top with a table s, for the support of a glass, shaving mug, or similar receptacle R, (indicated in dotted lines in Fig. 3) which is inverted over said table s, and with a brush shelf s', below, formed with recesses s², adapted to accommodate the narrow portion of a brush handle. Thus in Fig. 3, a tooth brush is shown in dotted lines as so supported on the shelf s'. The receptacle R, when inverted and resting upon the table s acts as a cover or canopy inclosing the brush bristles, thereby shielding them

from dust and keeping them clean and sanitary.

In order to lessen the liability of the displacement of the brushes by reason of jar or accidental contact therewith, I make the shelf s', inclined downward from front to rear, as shown more particularly in Fig. 3; and the positive retention of the shanks of the brushes within the recesses s², may be insured by the use of a rubber ring or band b, fitting around the edge of the shelf s', which edge may be formed for the purpose with an annular groove or depression s³, for the band b, the elasticity and resilience of which latter will hold it in place and also admit of its being removed from the groove s³, and moved temporarily above or below the shelf s', when it is desired to insert or withdraw a brush.

The standard S, terminates in a base S', which may be either in the form of a foot bearing or rest, as in Fig. 5, so that the device may be placed upon a flat surface, or the base S', may be of bracket form as in the first four figures of the drawings, and provided with slots s⁴, (Fig. 1,) for the accommodation of fastenings by which the device may be suspended upon a wall or other preferred support. This bracket form is desirable in that it is adaptable to the formation of a pocket like shelf s⁵, upon which a tube of dentifrice, a shaving soap, stick or the like may be accommodated.

The top of the table s, is preferably serrated or roughened to increase frictional contact with the bottom of the receptacle R.

While it is obvious that my holder may be made of any desired or suitable material I prefer glass or porcelain for sanitary reasons.

By my invention I attain a neat and compact construction and arrangement of parts adapted to the assembling and support in convenient and accessible relationship of dental or shaving brushes and their accessories. The shielding of the brush bristles from dust and contamination by contact with extraneous objects is an important sanitary advantage; and the grouping of the several articles to be used together saves time, and tends to prevent their loss or misplacement. It will be noted in this connection that by the reversing of the receptacle R, upon the table s, I not only utilize it as a

shield or canopy for the protection of the brush, but also insure its drainage and cleanliness, ready for immediate use when again wanted.

5. What I claim as my invention and desire to secure by Letters Patent is,

1. A holder of the character designated comprising a standard having a top portion for supporting a glass, an integral attaching portion with a pocket-like shelf upon one side of the standard and a brush shelf upon the opposite side of the standard having a recess to receive a brush handle.

10 2. A holder of the character designated comprising in a single element a standard with an offset portion for its attachment in position, a shelf at the upper end and a shelf

below the same having recesses and with an annular groove, and an elastic ring retained within said groove.

20

3. A holder of the character designated comprising in a single element a standard with an offset portion for its attachment in position, a shelf at the upper end and a shelf below the same having recesses and with an annular groove, and an elastic ring retained within said groove, there being a pocket-like shelf formed between the standard and its offset attaching portion.
